BUFFING WHEEL

John J. Lawler, Chicago, Ill., assignor to Ajax Buff Company, Chicago, Ill., a corporation of Illinois

Application February 8, 1950, Serial No. 143,048

10 Claims. (Cl. 51—193)

1

The present invention relates to a buffing wheel and a method of making the same, and more particularly to a buffing wheel provided with means for maintaining adjacent buffing wheels of a multi-wheel buffing assembly in spaced relation to permit heat flow through the assembly when in use and to an improved method of making such buffing wheels.

Conventional cloth buffing wheels comprise generally an annular buff formed of a plurality of fabric layers secured to a hub which is centrally apertured to receive a spindle or shaft. In use, a plurality of such wheels are secured to the shaft with the wheel hubs and buffs abutting to form an elongated, generally cylindrical buffing surface defined by the peripheral edges of the cloth buffers. Proper cooling of such a buffing assembly has always presented a problem in the art, and the difficulty of cooling has limited the size of the cylindrical buffing surface and/or the rotational speed of the assembly, and hence the work output from a given assembly.

The present invention provides an improved form of buffing wheel which may be assembled to form a buffing surface composed of any number of separate buffs which may be operated at higher rotational speeds than heretofore possible. It has actually been found that eight or more separate buffing wheels may be assembled on a spindle and operated at speeds up to 3600 revolutions per minute with no burning of the buff cloth caused by local overheating.

The buffing wheel of the present invention comprises generally an annular cloth buff having freely extending peripheral buffing edges and secured to a novel form of metal hub at the inner periphery of the buff. The hub carrier spacing means formed integrally therewith, which serve to maintain the separate buffing wheels of a buffing assembly in slightly spaced relation to one another, permit ventilation of the buffing assembly.

The spacing means extend axially beyond the end face of each wheel and, upon assembly of a plurality of the wheels, radial passages between the wheels are provided so that heat may be dissipated radially outwardly through such passages.

The present invention also contemplates an improved method of making buffing wheels in which the spacing means are formed integrally with the hub during the normal course of manufacture. The spacing means are positioned to extend beyond the hub during the assembly of the buff to the hub.

2

It is, therefore, an important object of the present invention to provide an improved form of buffing wheel provided with means for spacing the wheel from an adjacent wheel of a buffing assembly to permit dissipation of heat during use.

Another important object of the present invention is to provide an improved method of making a buffing wheel including the formation of spacing means integrally with the hub of the wheel and the extension of the spacing means beyond the wheel during assembly of the buff to the hub.

It is a further important object of the present invention to provide an improved buffing wheel including an annular cloth buff secured to a hub for mounting the wheel on a spindle, the hub being provided with integrally formed means extending axially therebeyond for spacing the wheel from an adjacent wheel of a buffing wheel assembly.

Still another important object of the present invention is to provide an improved buffing wheel assembly, the component wheels of the assembly including an annular cloth buff secured to a central hub and each of the hubs being provided with protuberance extending axially therebeyond for spacing the hubs from one another, thus providing radial heat dissipating passages between adjacent wheels of the assembly.

Other and further important objects of this invention will be apparent from the disclosures in the specification and the accompanying drawings.

On the drawings:

Figure 1 is a fragmentary, elevational view of a buffing wheel of the present invention;

Figure 2 is a vertical sectional view, with parts shown in elevation, illustrating the assembly of a plurality of the wheels of Figure 1 into a buffing assembly;

Figure 3 is an elevational view of a clamping element of the wheel of Figure 1;

Figure 4 is a sectional view taken along the plane IV—IV of Figure 3;

Figure 5 is an elevational view of a second clamping element of the wheel of Figure 1;

Figure 6 is a sectional view taken along the plane VI—VI of Figure 5;

Figure 7 is a fragmentary, exploded, sectional view illustrating the assembly of the wheel of Figure 1;

Figure 8 is a fragmentary sectional view illustrating the assembled buffing wheel of Figure 1;

Figure 9 is an elevational view of a modified

form of clamping element of the wheel of Figure 1;

Figure 10 is a sectional view taken along the plane X—X of Figure 9;

Figure 11 is an elevational view of an additional modified form of clamping element of the wheel of Figure 1;

Figure 12 is a sectional view of an assembled buffering wheel employing the modified element of Figure 11;

Figure 13 is an elevational view of another modified form of clamping element of the wheel of Figure 1; and

Figure 14 is a sectional view similar to Figure 12 illustrating the employment of the clamping element of Figure 13.

As shown on the drawings:

In Figure 1, reference numeral 10 refers generally to a buffering wheel of the present invention, including an annular cloth buff 11 and a hub 12.

The cloth buff 11 may be any of the numerous types of annular buff cloth construction known in the art. However, it is preferred that annular buffers formed of a plurality of elongated, bias-cut strips be employed. Such buffs are generally prepared by transversely gathering or pleating a plurality of superimposed strips, sewing the strips longitudinally down the center, as at 11a in Figures 2, 7 and 8, then doubling the strip upon itself along the sewed center line. The doubled strip is folded or pleated into an annular configuration having a smooth, generally rounded inner periphery 11d to fit the buffering wheel hub assembly 12. If desired, the folded annular buff may be sewed as at 11c in an annular pattern closely spaced from the inner periphery 11d.

The hub assembly 12 consists of a circular disk 13 and an annular ring 14 positioned on opposing sides of the buff 11 and overlying the inner periphery 11b of the buff. The disk 13, as best shown in Figure 3, is generally circular in outline and is provided with a centrally located, integrally formed cylindrical flange 15 defining an aperture 16 concentric with the disk. The central portion of the disk 13 extending radially outwardly from the flange 15 is provided with elongated, peripherally spaced, radially extending reinforcing ribs 17.

The outer periphery of the disk 13 is provided with integrally formed, radially outwardly extending, peripherally spaced teeth 18 provided with tapered outer terminal portions 19. As best shown in Figure 7, the teeth 18 are deformed prior to assembly of the hub 12 to lie in a plane substantially normal to the plane of the disk 13, for a purpose to be hereinafter more fully described.

The annular ring 14 is of slightly smaller outside diameter than the outside diameter of the disk 12 and is of approximately the same inside diameter as the annular buff 11. The ring 14 is provided with a plurality of circumferentially spaced apertures 20 in the form of slots defined by spaced slits extending radially inwardly of the ring 14 from the outer periphery thereof, the material 21 lying between the slits being deformed radially inwardly to lie against adjacent corresponding portions of the ring 14. Thus, the ring 14 is provided with a plurality of peripherally spaced, radially extending double-thickness portions.

The doubled portion 21 of the ring 14 corresponds in position to the teeth 18 of the disk 13. Thus, the assembly of the buffering wheel 10 may be carried out as shown in Figures 7 and 8 from

which it will be seen that the disks 13 and the ring 14 are positioned on opposing sides of the buff 11, and the teeth 18 may be forced completely through the corresponding portions of the buff 11 lying adjacent the inner periphery 11b of the buff. Following the forcing of the teeth 18 through the buff 11, the terminal portion 19 of each of the teeth is deformed downwardly to overlie the doubled portion 21 of the ring 14 to securely clamp the buff 11 between the cooperating disk 13 and the ring 14.

Axial separation of the disk and ring is thus prevented by means of the deformed terminal portions 19 of the teeth 18 in extended surface contact with the outer surface of the doubled-back portion 21 of the ring 14, and the edges of the apertures 20 prevent any unwarranted relative rotational movement of the component parts of the wheel. It will, of course, be appreciated that the doubled portion 21 of the ring 14 may be deformed from the plane of the ring only to the extent that it lies in a plane perpendicular to that of the ring, or roughly parallel to the teeth 18 when the components are disposed as shown in Figure 7. Following the forcing of the teeth 18 through the buff 11, both the teeth terminal portion 19 and the portions 21 of the ring 14 may be deformed radially inwardly to assume the position shown in Figure 8.

A modified form of annular ring is shown in Figures 9 and 10, this modification including an annular ring 22 of substantially the dimensions of the ring 14. The ring 22 is provided with a series of peripherally spaced apertures 23 defined by U-shaped slits formed radially inwardly of the ring 22 from its outer periphery with the slit portions of the ring being deformed inwardly as at 24 to form a double-thickness portion as hereinbefore described in connection with the portion 21 of the ring 14. The apertures 23 are positioned so as to receive the teeth 18, as hereinbefore described, and the assembly of the modified form of ring 22 is carried out substantially as hereinbefore described in connection with the first embodiment of the annular ring.

Another modified form of clamping element is shown in Figures 11 and 12. The element is designated by reference numeral 34 and comprises an annular ring quite similar to the ring of Figure 5. However, it will be noted that the ring 34 is provided with upstanding projections 35 extending approximately normal to the plane of the ring, the projections being formed during the punching, slitting or other working of the ring to form the circumferentially spaced apertures 36.

During assembly of the buffering wheel shown in Figure 12, the projections 38 remain in their upstanding position and the teeth 18 are deformed downwardly over the projections 35 to lie against the surface of ring 34. It will be appreciated that the projections 35 will serve to axially space the wheel 10 from the adjacent wheels of an assembly such as that illustrated in Figure 2.

In the additional modified form of clamping element of Figures 13 and 14, the element comprises an annular ring 40 similar to the ring 22 of Figure 9. In this case, the ring 40 is provided with a series of circumferentially spaced apertures 41, and those portions 42 of the ring lying radially inwardly of the apertures and immediately contiguous thereto are deformed from the plane of the ring, as best seen in Figure 14. The resulting protuberances 42 extend from the ring axially through a distance approximately equal to the thickness of the ring and serve to

axially space adjacent wheels of an assembly as hereinbefore explained.

It will be seen that the method of making the wheel includes the step of forming the disk 13 and the ring 14 by suitable processes, as by stamping, with the teeth 18 and the deflectable portions 21 being formed integrally therewith. Next, the teeth and the deflectable portions are deformed from the plane of the disk and ring, respectively, the teeth lying normal to the disk and the portions 21 either lying against the ring or normal thereto, as indicated in dotted outline in Figure 7. The teeth 18 are then forced completely through the buff 11 and into the space 20 defined by the deflected portions 21, followed by the radial deformation of the teeth, or the teeth and the portions 21, to the position of Figure 8.

In Figure 2, an assembly of several wheels upon a spindle or shaft 25 is shown. The shaft 25 is provided with an integral enlarged, radially outwardly extending flange 26 against which a generally circular mounting flange 27 is placed.

The mounting flange 27 is of approximately the same diameter as the ring 14 and is provided with a central annular flange 28 defining an axial aperture 29 receiving the shaft 25 therethrough. Following the positioning of the mounting flange 27 on the shaft 25, a buffering wheel 10 of the present invention is placed on the shaft with the flanges 15 of the disk 12 snugly receiving the shaft 25 and the inner lip of the flange 15 of the innermost wheel 10 abutting the corresponding lip of the flange 28.

The remaining buffering wheels 10 are then placed upon the shaft 25 with the teeth terminal portions 19 of successive wheels 10 abutting the outer peripheral portions of the disk 13 of the adjacent wheel 10. Following the assembly of the wheels 10 upon the shaft 25, a second mounting flange 30 is placed on the shaft 25 and a nut 31 is threaded upon the threaded end portion 32 of the shaft 25 to abut the outer surface of the flange 30.

It will be seen that each of the wheels 10, when assembled as shown in Figure 2, is separated from each adjacent wheel 10 by a quadruple thickness of metal or other material from which the hubs 12 of the wheels 10 are formed. Heat flow channels are formed between the adjacent teeth 18 of the hub 12, these channels permitting the radial flow of air from the hub 12 to the buff 11, thereby cooling the assembly as the same is rotated during use. The quadruple thickness of material separating adjacent wheels is provided by the annular ring 14, the inturned portion 21 of the ring 14, the teeth 19 of a given wheel, and the disk 13 of the wheel immediately adjacent the given wheel.

It will therefore be seen that I have in the present invention provided an improved form of buffering wheel provided with integrally formed means for permitting the vertical flow of air through the annular cloth buff of the wheel and from the wheel hub to carry heat vertically from the assembly, and it is thereby possible to employ an assembly of such wheels at high peripheral speeds and in large numbers without overheating or burning of the cloth buff. The heat developed upon use of the buffering assembly will be readily dissipated by the convection currents set up during normal operation of the buff, since these currents are free to travel radially through the buff and hub assembly. Thus, the spacing means of the present invention accommodate the flow of heat by convection from the assembly, and the

desired result, namely, the dissipation of heat generated upon rotation and use of the assembly, is accomplished thereby.

It will be understood that modifications and variations may be effected without departing from the scope of the novel concepts of the present invention.

I claim as my invention:

1. A buffering wheel comprising an annular cloth buff, a pair of clamping members having portions overlying opposed side surfaces of said buff, interengaging clamping means extending completely through said buff from one of said clamping members and having portions engaging the other of said clamping members, and means formed integrally with one of said clamping members and underlying said engaged portions of said clamping means, said integral means and said clamping means portions coacting for spacing said clamping members from the clamping members of an adjacent buffering wheel to provide for the passage of heat therebetween.
2. A buffering wheel comprising an annular cloth buff, a clamping member positioned on either side of said buff, radially extending portions struck from one of said members to define peripheral apertures therein, means on the other of said clamping members extending through said buff and the apertures in said first member into extended engagement with said radially extending portions to secure said members to said buff.
3. A buffering wheel comprising an annular cloth buff, a circular disk for abutting one side surface of said buff adjacent the inner periphery thereof, teeth formed integrally with said disk and extending therebeyond in a plane normal to the plane of said disk and extending through said buff, an annular ring abutting the opposing side surface of said buff and having apertures formed therein for receiving said teeth projecting beyond said buff, and additional inturned portions formed integrally with said ring and extending radially inwardly from said apertures for receiving the terminal ends of said teeth when deformed thereagainst, said additional portions forming an extra thickness of material extending axially beyond the buff for separating said buffering wheel from an adjacent wheel of a buffering wheel assembly to provide heat dissipation channels between the buffs of the buffering wheel assembly.
4. A buffering wheel comprising an annular cloth buff, an annular ring lying against one side surface of said buff and having peripherally spaced apertures and inwardly folded portions adjacent said apertures, and a circular disk having peripheral teeth formed therein to extend normally to the plane of the disk through said buff and the apertures of said ring, said teeth being deformed radially inwardly of the ring to lie against said inwardly folded portions thereof to thereby secure said ring and said disk to said buff on opposed sides thereof, with the teeth and the inturned portions being formed on one side of the wheel only and extending axially beyond said ring for abutting the adjacent wheel of a wheel assembly to form radially extending heat flow passages communicating with said buff.
5. A buffering wheel comprising an annular cloth buff, a circular disk for abutting one side surface of said buff adjacent the inner periphery thereof, teeth formed integrally with said disk and extending therebeyond in a plane normal to the plane of said disk and extending through said buff, an annular ring abutting the opposing side

surface of said buff and having apertures formed therein for receiving said teeth projecting beyond said buff, and additional out-turned portions formed integrally with said ring and extending approximately normal to the plane of the ring immediately adjacent said apertures for receiving said teeth thereabout when said teeth are deformed radially of said ring, said additional portions and the teeth deformed thereabout being provided on one side of the wheel only and thus serving to separate said buffing wheel from an adjacent wheel of a buffing wheel assembly to provide heat dissipation channels between the buffs of the buffing wheel assembly.

6. A buffing wheel comprising an annular cloth buff, a circular disk for abutting one side surface of said buff adjacent the inner periphery thereof, teeth formed integrally with said disk and extending therebeyond in a plane normal to the plane of said disk and extending through said buff, an annular ring abutting the opposing side surface of said buff and having apertures formed therein for receiving said teeth projecting beyond said buff, and deformed portions formed integrally with said ring immediately contiguous to said apertures, said deformed portions being displaced axially of the ring for receiving said teeth thereagainst when said teeth are deformed radially of said ring, said deformed portions and the teeth lying thereagainst being provided on one side of the wheel only and serving to separate said buffing wheel from an adjacent wheel of a buffing wheel assembly to provide heat dissipation channels between the buffs of the buffing wheel assembly.

7. A buffing wheel comprising an annular cloth buff, a circular disk for abutting one side surface of said buff adjacent the inner periphery thereof, teeth formed integrally with said disk and extending therebeyond in a plane normal to the plane of said disk and extending through said buff, an annular ring abutting the opposing side surface of said buff and having apertures formed therein for receiving said teeth projecting beyond said buff, and deformed portions formed integrally with said ring to define a plurality of circumferentially spaced local protuberances extending axially of the ring and receiving said teeth thereagainst, said protuberances and the teeth lying thereagainst being provided on one side of the wheel only and cooperating to define therebetween radial heat dissipating channels of a depth equal to the thickness of said teeth and the distance through which the protuberance is displaced from the plane of the ring.

8. A buffing wheel comprising an annular cloth buff, clamping members positioned on opposing sides of said buff adjacent the inner periphery thereof, clamping means extending through said buff from one of said clamping members and engaging said other clamping member to secure said clamping members to said buff, said other clamping member having axially extending outwardly projecting embossed portions, and said

clamping means including portions lying against said embossed portions, said embossed portions and said clamping means portions lying thereagainst serving to separate said buffing wheel from an adjacent wheel of a buffing wheel assembly to provide heat dissipation channels between adjacent wheels when assembled.

9. A buffing wheel comprising an annular cloth buff, a circular disk for abutting one side surface of said buff adjacent the inner periphery thereof, teeth formed integrally with said disk and extending therebeyond in a plane normal to the plane of said disk and extending through said buff, an annular ring abutting the opposing side surfaces of said buff and having apertures formed therein for receiving said teeth projecting beyond said buff, said ring having axially extending outwardly projecting embossed portions immediately radially inwardly of said apertures for receiving said teeth thereagainst when said teeth are deformed radially inwardly of the ring, said embossed portions and the teeth lying thereagainst being provided on one side of the wheel only and coacting to define radial heat dissipating channels of a depth equal to the embossed height of one of said embossed portions plus the thickness of one of said teeth.

10. A buffing wheel comprising an annular cloth buff, a circular disc abutting one side surface of said buff adjacent the inner periphery thereof and having peripherally spaced teeth extending through said buff in a plane approximately normal to the plane of said disc, a clamping member abutting the other side surface of said buff adjacent the inner periphery thereof and having peripherally spaced openings for receiving the end portions of said teeth projecting beyond said buff, said projecting teeth ends being formed radially to overlie said clamping member and said clamping member having peripherally spaced portions extending axially of the plane thereof away from said buff to underlie said teeth ends and space the same from the adjacent surface of said clamping member, whereby when a plurality of said wheels are assembled in laterally contacting relationship said teeth ends and underlying portions provide air passages between adjacent buffs.
